GUARD FOR PORTABLE POWER SAWS

Joe V. Doug, Fresno, Calif.

Application December 1, 1951, Serial No. 259,370

6 Claims. (Cl. 143—159)

1

The present invention relates generally to portable power driven tools and more particularly to an improved guard for portable power saws.

Portable power saws have been found effective in minimizing the labor required in building construction and the like but have proved a source of such frequent injury to their operators as to substantially reduce their utility. In many instances the use of such power driven tools has been banned because of the excessive injury rate.

Such saws usually employ an electric motor having driving connection to a circular saw blade and are provided with a handle for portability. A housing is rigidly mounted on the motor in shielding relation to a portion of the blade usually enveloping substantially half of the periphery of the blade. The housing can be conveniently visualized as providing an edge from which the blade is extended approximately diametrically related to the blade. A guard is pivotally mounted on the housing for movement between a position in shielding relation to a portion of the exposed periphery of the blade and a position retracted therefrom so that in utilizing the tool the blade can be caused to transverse a board or the like while the guard is retracted from the blade. When so employed, it is the usual practice for the operator to guide the saw by means of the handle and by grasping the guard while pivoted into its retracted position. As it is sometimes necessary to apply considerable pressure in causing the saw to progress, sufficient force is frequently imposed upon the guard to cause the articulately connected guard and housing suddenly to buckle, thrusting the operator's fingers forcibly into the driven blade. Although such operation of portable power driven saws is generally forbidden, it has been found that the dangerous practice continues unless the saws are banned or substantially modified in structure.

An object of the present invention is to provide an improved guard for portable power driven saws and the like that is conducive to improved safety in the utilization of such tools.

Another object is to provide a guard of the character described providing a grasping handle so positioned as to preclude movement of an operator's fingers into the saw blade even if the guard and housing on which it is mounted buckles in the described manner.

Another object is to provide an improved guard for power driven saws providing a handle which when grasped with the guard in closed position locks the guard in such position.

2

Further objects and advantages are to provide improved elements and arrangements thereof in a device of the character and for the purposes set forth that is economical to produce, fully effective in obviating the described hazards incident to power saw operation, and that achieves improved safety characteristics without in any way detracting from operational convenience.

Still further objects and advantages will become apparent in the subsequent description in the specification.

Referring to the drawing:

Fig. 1 is a side elevation of a portable power driven saw employing a saw guard embodying the principles of the present invention.

Fig. 2 is an end elevation of the saw and saw guard.

Fig. 3 is an enlarged fragmentary side elevation of the saw and saw guard with a cover for a latching mechanism shown in section, as viewed from line 3—3 in Fig. 2.

Fig. 4 is a section of the latching mechanism of the movable guard, as taken on line 4—4 in Fig. 2.

Fig. 5 is a section through the latching mechanism, as viewed from line 5—5 in Fig. 3.

Fig. 6 is a section through the latching mechanism as taken on line 6—6 in Fig. 3.

Referring in greater detail to the drawing:

An exemplary portable power driven saw is illustrated in Figs. 1 and 2 of the drawing at 10. The saw is constructed with a housing 11 having an upwardly and laterally extending handle 12 whereby the saw may be conveniently carried and manipulated during sawing operations. The housing 11 encloses an electric motor 13 having a drive shaft 14 extended axially endwardly therefrom. A circular saw blade 15 is secured concentrically to the shaft.

The saw is also provided with a flat rectangular guide plate 19 whereby the saw may be guided along the surface of a board 20 while the board is being sawed to a desired dimension or shape. Although the saw illustrated is electrically powered, any power driven saw or other suitable tool may utilize the subject guard subsequently described without departing from the spirit or scope of the present invention. In order to protect operators of the tool, a guard 25 is rigidly mounted on, or constitutes an integral part of, the housing 11 and encloses an upper portion of the periphery of the saw blade 18. The structure described to this point is essentially conventional and simply illustrates a tool in connection with which the guard of the present invention readily demonstrates its utility.

A movable guard 26 is mounted on the saw by forming an ear 30 on a portion of the fixed guard 25. The movable guard comprises a pair of concave guard members 31 which are bolted together, as at 32 in facing relation forming an open arcuate saw pocket 33 and a closed lever pocket 34. Each guard member 31 of the movable guard has an ear 35 extended endwardly therefrom with the ears in alignment transversely of the guard. A pivot rod 36 is passed axially through the singular ear 30 and the pair of ears 35 on the movable guard with the pivot rod pinned at 37 to the ear 30 on the housing to prevent rotation therein and with the ears 37 rotatably mounted on the pivot rod.

An elongated arcuate handle 38 is formed in substantially concentric relation to the saw blade 18 having handle legs 39 at each end thereof whereby it is integrally connected to the movable guard 26. A finger recess 40 is formed between the handle and the movable guard for receipt of the fingers of an operator during saw operations. A movable guard without a handle has been employed in portable power driven saws before the improvement of the present invention. In the use of such saws without the handle attached to the movable guard, operators frequently grasp the saw guard with the described hazard and frequently resulting injury. A significant feature of the present invention is the provision of the handle in sufficiently spaced relation to the saw pocket 33 as to preclude extension of an operator's fingers into the blade while grasping the handle.

The movable guard 26 is constantly urged to its pivotally closed position in shielding relation to the saw blade by securing a cup 42 to one end of the pivot rod 36 and locating a torsion spring 43 in circumscribing relation to the pivot rod with one end thereof anchored to the cup 42 and its opposite end anchored to the movable guard with the spring under initial torque.

It is desirable at times, for carrying convenience and the like, to prevent relative pivotal movement between the saw guard 26 and the saw housing 11 when the saw guard is in its closed position shielding a portion of the periphery of the saw blade. The movable guard is automatically latched, and may be manually unlatched, in closed position by a latching mechanism indicated generally by the reference numeral 44. A boss 45 is formed integrally with the stationary saw guard 25 having an inner face 46 concentric to the pivot rod 36. A frusto-conical recess 47 is formed in the boss 45 extending inwardly of its face 46 relatively radially outwardly of the pivot rod. A lug 48 is formed axially of one ear 35 of the movable guard 26. A bore 49 is formed through the lug 48 radially of the pivot rod 36 and in axial alignment with the recess 47 when the movable guard is in its closed position.

An elongated cylindrical latch pin 50 is mounted for longitudinal slidable movement in the bore 49. The latch pin is provided with an enlarged annulus 51 which is longitudinally slidable in a counterbore 52 formed in the lug 48 concentrically of the bore 49. A helical compression spring 53 is located under initial compression between the bottom of the counterbore 52 and the annulus 51 in circumscribing relation to the latch pin 50 continually urging the latch pin to a retracted position from the recess 47.

An elongated latch lever 56 is pivotally mounted between its ends on a pivot pin 57 extended through the members 31 of the movable guard 26. A manually operable grip end 58 of the latch

lever projects into the lever pocket 34 of the movable guard and has a portion thereof disposed in the finger recess 40 between the handle 38 and guard 26. An opposite pin actuating end 59 of the latch lever extends through an L-shaped slot 60 formed through the movable guard. An aperture 61 is formed through the end 59 of the latch lever through which one end of the latch pin 50 extends. A helical compression spring 62, of greater compressive resistance than the spring 53, is located under initial compression in circumscribing relation to the latch pin between the pin actuating end 59 of the latch lever and the annulus 51 of the latch pin. The outer end of the latch pin is provided with external screw threads 63 and a nut 64 is threaded thereon to maintain the latch lever and latch pin in assembled relation and to provide manipulation of the latch pin on actuation of the latch lever.

In order to preclude interference with the actuation of the latch pin due to the presence of dirt and dust therein, a sheet metal cover 56 is preferably provided for the movable portions of the latching mechanism. This cover has a pair of ears 66 through which screws 67 are passed and engaged in the movable guard.

The inner face of the boss 45 on the housing is beveled at 10 to form an approach for the latch pin 50 to guide the latch pin inwardly whenever the movable guard is rotated to closed position to preclude positive engagement of the pin with the boss in the event the pin is projecting beyond the outer cylindrical surface of the lug 48. In the event the latch pin is extending beyond the lug on inward pivotal movement of the movable guard the latch pin is cammed inwardly by the beveled approach 10 until the pin is in axial alignment with the recess 47 in the boss 45.

Operation

The operation and utility of the present invention are believed to be apparent and are briefly summarized at this point. The portable power driven saw is adapted conveniently to cut lumber to the desired sizes and shapes with a substantial portion of the periphery of the saw blade 18 shielded by the fixed guard 25. The movable guard 26 normally is pivoted inwardly by the torsion spring 62 in shielding relation to the lower portion of the periphery of the saw. During sawing operations, the saw is manipulated by an operator grasping the handle 12 for manually guiding the saw to desired positions to attain the proper saw cut. The guide plate 19 may be rested on the upper surface of the piece of lumber so that a constant depth of cut is maintained.

It is sometimes desirable to carry the saw by the handle 38. In such instances, the operator simply grasps the handle 38 on the movable saw guard 26. With the hand in its natural position grasping the handle 38, the fingers of that hand extend through the finger recess 40 over the manually operable end 58 of the latch lever 56. The manually operable end of the latch lever is thus depressed which forces the latch pin 50 into the frusto-conical recess 47 and precludes outward pivotal movement of the saw guard from its position in shielding relation to a portion of the periphery of the saw blade. Although the helical compression spring 53 urges the latch pin to a retracted position, inasmuch as the spring 62 has a greater compressive resistance than the spring 53, depression of the manually operable end 58 of the latch lever moves the actuating end 59 of the latch lever inwardly toward the

lug 48 thereby urging the latch pin 50 into the recess 47. Thus, as long as the handle 38 is grasped and the end 58 of the latch lever depressed, the saw guard can not pivot outwardly from rest position.

As the saw is initially guided into a piece of lumber to form a cut therein, the movable guard is located over a portion of the periphery of the saw. As the portable saw is moved along the piece of lumber during cutting operations, the leading edge of the lumber engages the inner edges of the movable guard pivoting the movable guard rearwardly around its pivot rod 36 until it reaches the position shown in dashed lines in Fig. 1 of the drawing. While the movable saw guard is in this rearwardly projected position, the guard handle 38 is conveniently located to be grasped by the otherwise free hand of the user of the saw so that the saw may be guided more conveniently and more accurately than heretofore possible. Further, if the operator's thrust on the handle is excessive and the guard 26 buckles on the housing 11, the guard simply moves to closed position and, the operator's hand being on the handle 38, no hazard is encountered. When the piece of lumber has been completely cut and the saw blade 15 moves free of the piece of lumber, the torsion springs 43 urges the movable saw guard back to closed position in shielding relation to the saw blade.

The device of the present invention is economical to produce, successfully obviates the described and similar hazards incident to power tool operation, and provides auxiliary means facilitating accurate, safe and dependable operation.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention what I claim as new and desire to secure by Letters Patent is:

1. In combination with a portable power driven saw having a rotatable circular saw blade and a fixed guard enclosing a portion of the blade with a peripheral portion of the blade extended from the fixed guard for work piece engagement, a pivot rod rotatably mounted in the housing in axial parallel relation to the blade, an elongated arcuate guard having a concave edge formed with a channel longitudinally thereof and an opposite edge, said arcuate guard being mounted in fixed radial position on the rod for pivotal movement upon rod rotation between a closed position with the channel fitted over the extended periphery of the blade and an open position retracted from the blade, a handle integral with the arcuate guard having a grip portion in spaced relation to the edge of the guard opposite to the arcuate edge and defining a finger recess therebetween, said grip portion having a groove formed therein disposed toward the arcuate guard, the fixed guard having a bore formed therein adjacent to the rod, an elongated latch pin mounted for longitudinal reciprocal movement in the rod in alignment with the bore when the arcuate guard is in closed position, a compression spring urging the pin into a position retracted from the bore, a latch lever pivotally mounted in the handle with an operating end positioned in the groove of the grip and an ac-

tuating end provided with an opening slidably receiving the latch pin, and a compression spring mounted on the latch pin having an end in abutting engagement with the actuating end of the latch lever.

2. A portable saw comprising a power driven blade, a fixed guard mounted in housing relation to a portion of the blade, a handle rigid with the fixed guard for manually urging the saw blade in a predetermined direction in the plane of the blade through work pieces to be cut, and a safety guard pivotally mounted on the fixed guard rearwardly of the blade relative to the predetermined direction of movement thereof for pivotal movement between a position extended forwardly from its pivotal mounting, and a position extended rearwardly therefrom, said safety guard having an edge fitted over the blade in its forward position which edge is adapted slidably to rest on a work piece being sawed when in its rearward position, said safety guard having a handle integral therewith in spaced relation to the edge fitted to the blade and having a finger recess between said handle and safety guard for auxiliary urging of the blade through work pieces when the guard is in rearward position.

3. A portable saw comprising a power driven saw blade having an upwardly disposed periphery and a downwardly disposed periphery engageable with a work piece, a fixed guard fitted downwardly over the upwardly disposed periphery of the saw blade, an upwardly disposed handle adapted for motivation of the saw in a predetermined direction relative thereto over a work piece, whereby the fixed guard has forward and rearward end portions, a safety guard pivotally mounted on the rearward end portion of the fixed guard and downwardly and forwardly extended therefrom below the saw blade and having an edge fitted upwardly over the lower periphery of the saw blade, said edge of the safety guard being slidably engageable with a work piece being sawed by the blade upon forward movement of the saw to cam the safety guard into a rearwardly and upwardly pivoted position slidably rested on the work piece, said safety guard having a handle integral therewith oppositely disposed from the saw guard relative to the blade and defining a finger recess between the handle and the guard in spaced relation to the edge of the guard fitted upwardly over the blade whereby a workman's hand grasping the handle on the safety guard is at all times spaced from the saw blade independent of the pivotal positioning of the safety guard and auxiliary motivation of the saw by means of said handle made possible when the safety guard is slidably rested on a work piece.

4. In combination with a portable power driven saw having a guide plate slidable over a work piece to be sawed, a motor mounted on the guide plate, a saw blade connected to the motor having a periphery extended below the guide plate for work piece engagement, a fixed guard mounted on the motor and fitted downwardly over the saw blade terminating in upwardly spaced relation to the guide plate, and a handle mounted on the motor adapted for manual urging of the guide plate, motor, blade, and fixed guard in a predetermined direction relative thereto over a work piece whereby the fixed guard has a forward and a rearward end portion; a safety guard pivotally mounted on the rearward end portion of the fixed guard forwardly extended beneath the guide plate and fitted upwardly over the

lower periphery of the saw blade; said safety guard having a handle integral therewith oppositely disposed from the safety guard to the saw blade providing a finger recess between the handle and the guard in spaced relation to the saw blade, the safety guard being rearwardly and upwardly pivotal to a rearwardly raised position with all portions thereof above the guide plate and having a saw blade receiving edge engageable with a work piece forcibly to pivot the safety guard rearwardly and upwardly upon forward movement of the saw and an extended end adapted to rest upon and slide over a work piece when the safety guard is rearwardly and upwardly pivoted with the handle upwardly disposed for grasping and auxiliary motivation of the saw.

5. In combination with a portable saw having a power driven saw blade having an upwardly disposed periphery and a downwardly disposed periphery engageable with a work piece, a fixed guard fitted downwardly over the upwardly disposed periphery of the saw blade, an upwardly disposed handle adapted for motivation of the saw in a predetermined direction relative thereto over a work piece whereby the fixed guard has forward and rearward end portions, a safety guard pivotally mounted on the rearward end portion of the fixed guard and downwardly and forwardly extended therefrom below the saw blade and having an edge fitted upwardly over the lower periphery of the saw blade, said edge of the safety guard being slidably engageable with a work piece sawed by the blade upon forward movement of the saw to cam the safety guard into a rearwardly and upwardly pivoted position slidably rested on the work piece, said safety guard having a handle integral therewith oppositely disposed from the saw guard relative to the blade and defining a finger recess between the handle and the guard in spaced relation to the edge of the guard fitted upwardly over the blade whereby a workman's hand grasping the handle on the safety guard is at all times spaced from the saw blade independent of the pivotal positioning of the safety guard and auxiliary motivation of the saw by means of said handle made possible when the safety guard is slidably rested on a work piece, and a spring interconnecting the safety guard and the fixed guard urging the safety guard into its forwardly extended position fitted upwardly over the lower periphery of the saw blade.

6. In combination with a portable power driven saw having a guide plate slidable over a work piece to be sawed, a motor mounted on the guide plate, a saw blade connected to the motor having a peripheral portion extended below the guide plate for work piece engagement, a fixed guard mounted on the motor and fitted downwardly

over the saw blade terminating in upwardly spaced relation to the guide plate, and a handle mounted on the motor adapted for manual urging of the guide plate, motor, blade, and fixed guard in a predetermined direction relative thereto over a work piece whereby the fixed guard has a forward and a rearward end portion, a safety guard pivotally mounted on the rearward end portion of the fixed guard forwardly extended beneath the guide plate and having an edge fitted upwardly over the lower peripheral portion of the saw blade, said safety guard having a handle integral therewith oppositely disposed from the safety guard to the saw blade providing a finger recess between the handle and the guard in spaced relation to the saw blade, the safety guard being rearwardly and upwardly pivotal to a rearwardly raised position with all portions thereof above the guide plate and the saw blade receiving edge being engageable with a work piece and shaped so as to cam the safety guard rearwardly and upwardly upon forward movement of the saw and the safety guard having an extended end adapted to rest upon and slide over a work piece when the safety guard is rearwardly and upwardly pivoted with the handle upwardly disposed for grasping and auxiliary motivation of the saw, resilient means interconnecting the safety guard and the fixed guard urging the safety guard into its forwardly extended position fitted upwardly over the lower peripheral portion of the saw blade, a latch pin mounted for longitudinal reciprocal movement toward and from the fixed guard and unitary pivotal movement with the safety guard, the fixed guard having a bore therein adapted to receive the pin when the safety guard is fitted upwardly over the lower peripheral portion of the guard, resilient means urging the pin into a position retracted from the bore, a latch lever pivotally mounted in the handle of the safety guard and disposed for finger engagement in the recess, and resilient means interconnecting the lever and the pin urging the pin toward the fixed guard in response to pivotal movement of the lever toward the handle.
